CLAIM

The ornamental design for a scope mount, as shown and described.

DESCRIPTION

FIG. 1 is a right side elevational view of a scope mount, showing my new design, the left side being a mirror image of the side shown;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side and front perspective view thereof;

FIG. 7 is a right side elevational view of a second embodiment of a scope mount, showing my new design, the left side being a mirror image of the side shown;

FIG. 8 is a top plan view thereof;

FIG. 9 is a bottom plan view thereof;

FIG. 10 is a front elevational view thereof;

FIG. 11 is a rear elevational view thereof; and,

FIG. 12 is a left side and front perspective view thereof.
